(57) **CLAIM**

The ornamental design for an eyeglass display, as shown and described.

DESCRIPTION

FIG. 1 is a perspective view of an eyeglass display in accordance with the present invention;

FIG. 2 is a top plan view of the eyeglass display as shown in FIG. 1;

FIG. 3 is a front elevational view of the eyeglass display shown in FIG. 1, with the back view being a mirror image thereof;

FIG. 4 is a bottom plan view of the eyeglass display as shown in FIG. 1;

FIG. 5 is a left side elevational view of the eyeglass display as shown in FIG. 1; and,

FIG. 6 is a right side elevational view of the eyeglass display as shown in FIG. 1.

The broken lines are for illustrative purposes only and form no part of the claimed design.
